C. E. WEISS

GUN, PISTOL, AND THE LIKE

Filed Sept. 17, 1921

by Lawrence Langner

Aug.

UNITED STATES PATENT OFFICE.

CARL ERHARD WEISS, OF NUEREMBERG, GERMANY.

GUN, PISTOL, AND THE LIKE.

Application filed September 17, 1921. Serial No. 501,416.

To all whom it may concern:

Be it known that I, CARL ERHARD WEISS, citizen of Germany, residing at Nuremberg, Bavaria, Republic of Germany, have invented new and useful Improvement in Guns, Pistols, and the like, of which the following is a specification.

The invention relates to guns, pistols and the like and more particularly to automatic pistols. In order to render guns of large caliber suitable for practice in rooms, yards and the like barrels of narrow bore for small caliber ammunition are inserted into the barrel of large caliber. The great drawback of these inserted barrels as heretofore constructed is that the guns had to be taken to pieces before the narrow bore barrels could be inserted. To overcome this disadvantage various means of attachment (keys, holding rings, nuts and the like) have been used, by the aid of which the auxiliary barrel could be inserted into the large caliber barrel from the front and the dismantling of the gun rendered unnecessary. The known means for effecting this have the disadvantage that they are separate from the barrel and easily were lost owing to their small size and, furthermore, were not easy to handle. The auxiliary barrel was also more or less weakened by grooves, screw-thread, flat portions and the like just in the place where the gas pressure is greatest, whereby the life of the auxiliary barrel was very unfavourably influenced.

The invention relates to an auxiliary barrel for guns, the means of attachment of which avoid the beforementioned disadvantages, allow the barrel to be inserted without the necessity of taking the gun to pieces and ensure an absolutely tight seat of the small caliber barrel within the large caliber barrel.

In the accompanying drawings—

Fig. 1 shows a longitudinal section through part of the two barrels with the means of attachment not in operation and

Fig. 2 a similar view with the means of attachment in operation.

Fig. 3 is a longitudinal section of the auxiliary barrel nut.

The self-contained means of attaching or affixing the auxiliary barrel *b* within the

large caliber barrel *a* comprise an annular groove *d* in and eccentric to the axis of the auxiliary barrel into which fits an eccentric split ring *e*. If the thinnest part of the ring *e* rests in the shallowest part of the groove *d*, the surface of the ring *e* is flush with the surface of the auxiliary barrel *b* and the latter can be easily inserted into the large caliber barrel *a*, see Fig. 1. By turning the auxiliary barrel after its insertion through an angle of 180°, the thickest part of the ring *e* is situated in the shallowest part of the groove *d* and in this position of the parts the ring *e* projects beyond the surface of the barrel, see Fig. 2. In this position the ring abuts against a shoulder formed by a contraction in the large caliber barrel *a*, so that by tightening a nut the inserted barrel is firmly fixed within the outer large caliber barrel.

The auxiliary barrel is inserted into the large bore barrel in the following manner: The small barrel is pushed into the large barrel from the front until the ring projects from the rear end of the large barrel. A screw-driver or the screwdriver-like end of the loading spoon supplied with each outfit is then inserted into the slit of the ring, so as to prevent the ring from rotating, and the small barrel is then turned through an angle of 180° from the position Fig. 1 into the position Fig. 2. The nut *f* as in Fig. 3 usually riding upon the screw-threaded outer end of the small barrel is then screwed against the front end of the large barrel, whereby the small barrel is finally fixed in position.

It will be understood that we do not limit ourselves to the exact dimensions or proportions of groove and ring or to any definite means for attachment used in conjunction with the means described.

What I claim as my invention and desire to secure by Letters Patent is—

1. The combination with a gun, of large caliber, of a barrel of small caliber adapted to be inserted into the large caliber barrel, an annular eccentric groove in said small caliber barrel and an eccentric split ring in said groove.

2. The combination with a gun, of a large caliber barrel, of a small caliber barrel adapt-

ed to be inserted into the large caliber barrel, an annular eccentric groove in the rear of said small caliber barrel, an eccentric ring in said groove, said groove and ring being adapted to be turned relative to each other, and a nut for securing said small caliber barrel at the front end of said large caliber barrel.

In testimony whereof I have signed my name to this specification in the presence of 10 two subscribing witnesses.

CARL ERHARD WEISS.
